C. DAY & G. E. WINDELER.
VALVE MECHANISM FOR AIR COMPRESSORS.
APPLICATION FILED JUNE 13, 1912.

1,088,264.

Patented Feb. 24, 1914.

UNITED STATES PATENT OFFICE.

CHARLES DAY AND GEORGE E. WINDELER, OF STOCKPORT, ENGLAND, ASSIGNEES TO
GENERAL ELECTRIC COMPANY, A CORPORATION OF NEW YORK

VALVE MECHANISM FOR AIR-COMPRESSORS.

1,088,264.

Specification of Letters Patent.

Patented Feb. 24, 1914.

Application filed June 13, 1912. Serial No. 703,392.

To all whom it may concern:

Be it known that we, CHARLES DAY and GEORGE E. WINDELER, subjects of the King of Great Britain, and residing at Stockport, county of Cheshire, England, have invented certain new and useful Improvements in Valve Mechanism for Air-Compressors, of which the following is a specification.

The present invention relates to valve mechanism for multi-stage high pressure reciprocating air compressors and has for its object to improve their construction, whereby they are rendered silent, simple in construction and more effective in their action.

10 For a consideration of what we believe to be novel and our invention attention is directed to the accompanying description and claims appended thereto.

In the accompanying drawing which illustrates one of the embodiments of our invention, Figure 1, is a view in side elevation of a two stage air compressor; Fig. 2 is a sectional view of the high pressure suction and delivery valves and casings; Fig. 3 is a sectional view of the atmospheric suction valves and their casing; Fig. 4 is a sectional view of the low pressure delivery valves and their casing; Figs. 5 and 6 are sectional and plan views of a high pressure disk valve; Figs. 7 and 8 are sectional and plan views of high pressure valve seats; Figs. 9 and 10 are sectional and plan views of a low pressure valve seat; Figs. 11 and 12 are sectional and plan views of a low pressure delivery valve stop; Figs. 13 and 14 are sectional and plan views of a low pressure suction valve stop; Figs. 15 and 16 are sectional and plan views of a low pressure delivery valve, and Figs. 17 and 18 are sectional and plan views of a low pressure valve seat.

In Fig. 1 is shown a two stage compressor arranged to deliver air at about 1000 pounds pressure per square inch. It is adapted chiefly for supplying fuel in the form of oil to high compression internal combustion engines, and for supplying starting air thereto, although it can be used for other purposes. The compressor has two pistons 19 and 20 arranged in tandem and driven by the crank shaft 21. Each piston has its own cylinder, that of the low pressure stage being considerably larger in diameter than that of the high pressure stage. Air is admitted to the low pressure cylinder by valve means located in the casing 22 and is de-

livered by valve means located in the casing 23. At the upper end of the compressor is a casing 24 containing a suction valve means that receives air from the valve casing 23 after it has passed through an inter-cooler, and also a delivery or discharge valve.

It will be observed that the suction or inlet valves and the delivery valves of the low pressure cylinder are situated substantially in the plane of division between the cylinders. The advantage of this resides in the fact that short passages can be employed and that the cooling chamber of the delivery valve may receive its supply of cooling water directly from the water jacket of the cylinder or cylinders. The high pressure valves are located at the top of the cylinder and open directly into the cylinder thereby avoiding all passages between except such as are in the valve parts.

It is a serious problem to make the valves of a high pressure air compressor operate silently and at the same time effectively, and especially if the compressor is driven at a fairly high speed. It is also a difficult matter to make the valves and their seats stand up under the hard service to which they are subjected. The purely mechanical features are sufficiently complex of themselves but in addition to this the relatively high temperatures of the compressed air must be taken into account, also the carbon deposit due to the lubricating oil used on the pistons. We have solved this problem by using thin disk valves made out of a tough and preferably hard metal which are carefully ground or finished to size as are also their coöperating seats and stops or motion-limiting devices. By preference the movement of these valves in opening and closing is limited to a very small amount. As an example, if the best results are to be obtained, the total valve movement should not exceed in amount the thickness of the valve itself.

Referring to Fig. 3, 22 indicates the admission valve casing. It is bored centrally to receive the upper and lower spring holders and valve receiving members or stops 25 which engage opposite sides of internal shoulders 26, said holders being slipped into position from opposite ends of the bore. Above and below the holders (that is, at the side of each remote from the other) are valve seats 27 of the character best shown in Figs. 9 and 10. Each seat is formed on the lower

side or end of a valve receiving member or plug 28, said plug having a shoulder 29 for securing the holder in place, a series of radial openings 30, a large axial opening 31, and small axial holes 32 with which it communicates. The cover 33 rests on and forces the plug and spring holder and valve stop firmly into place. As an additional means for securing a pressure tight joint between the plug and holder, a soft copper washer 34 is located between them. It will be noted that the end of the plug carrying the valve seat 27 projects into the member 25 forming the valve stop and said parts are therefore interlocked or intermeshed. The openings, holes or ports 30, 31 and 32 receive air from a chamber that surrounds the plug and communicate with the passage 35 leading through the casing to the atmosphere. This arrangement is duplicated at the bottom so that a large amount of air will be admitted to the compressor cylinder. The admission of air is controlled by a rotatable throttle valve 36 which is mounted on a screw threaded stud 37. A wing nut is employed to hold the valve in any given position. By moving this valve toward or away from its seat the total amount of air passing through the compressor can readily be varied. In other words, it forms a very simple and reliable governing means.

Figs. 11 and 12 show the spring holders which also act as valve stops. Each holder is made in a single piece and is provided externally with a beveled face that engages the shoulder 26 in the valve casing and an annular centering enlargement or flange at or near the upper end. It is provided with a plurality of axial holes, passages or ports 38 through which the air passes on its way to the port 39 that communicates with the low pressure cylinder. It is also provided with a cylindrical chamber 40 which connects all of the passages 38, receives the projection on the plug carrying the low pressure valve seat 27, forms a chamber for the disk valve 39, and also acts as a stop to limit its opening movement. The holder is also counterbored at 40° to receive the coiled compression spring 41 which normally holds the valve against its seat. Although springs are shown in connection with these valves, in a great many cases they will be found unnecessary. Where they are required the arrangement shown will be found satisfactory. The valve itself is made in the form of a thin hard disk which is carefully ground until both of its faces are true and parallel to each other. The seats 27 are also ground and should be perpendicular to the axes of the valves. The amount of valve movement is small so that the pounding effect of the valves is reduced to a small value. Said effect in any event is small because the mass of the valve is small. The surface of the

stop should be flat and parallel with the seat so that all parts of the valve will move a uniform distance therefrom. The arrangement of the valves and the supply ports 38 is important. The air should be delivered to the valve over a wide area so as not to cause undue restriction, and on the other hand the valve should lift freely and its movement should be reduced to a minimum. By extending the ports 38 to a point above the flat surface forming the stop, as shown in Figs. 3 and 11, air will freely pass over the valve when open and enter the row of ports 32 in the plug. By using numerous and relatively small ports instead of one large one a much better distribution of the air is obtained with less liability of bad operation of the valve. The arrangement also permits the air on the compression stroke to have access to the under side of the valve and close it. The valve as before stated can be actuated solely by pressure changes or it may be aided by the spring to move in one direction. The disk valve is provided with a central opening 45 which, although not utilized in the present valve, is necessary in the low pressure delivery valve as will be seen later. It is preferable to make these two valves interchangeable, and for this reason the hole is provided. The holder 25 is also provided with a tapped hole 46, Fig. 11, to receive a tool, by means of which it can be pulled out of the casing when necessary. As the piston of the compressor descends on its suction stroke, a suction is created that moves both of the valves off of their seats against the light opposing forces due to the springs. Air then flows from the inlet past the valve 36 into the passages 35, 31 and 32, around the outer edge of the valve into the passages 38 and port 39 to the low pressure cylinder. When the piston starts on its compression stroke the suction effect ceases and the reversed pressure and the springs 41 close the valves and the air contained in the cylinder is compressed to the end of the stroke, when it is delivered by the discharge valves to the intercooler or to the high pressure cylinder as desired.

In Fig. 4 is shown the low pressure delivery valve. 23 indicates the casing which is provided with cooling chambers 47 that are connected to the cooling system of the air compressor cylinder or cylinders. The casing is bored axially, and in the central portion thereof is a ring shaped member 48 that is provided with beveled surfaces on opposite sides to receive the valve securing members or seats 49. Two of these seats are used and are of the construction best shown in Figs. 17 and 18. Each seat has a beveled peripheral shoulder 50 which rests on the beveled surface of the ring member 48. It is provided with a plurality of holes or passages 51 through which the air flows. The

valve seats are cut away on their adjacent sides at 52 so that when they are mounted in place an annular chamber 53 is formed to which air enters from the port 54, the latter being connected with and receiving air from the low pressure cylinder of the compressor. As an illustration, the air admitted to the valve casing may be under a pressure of 90 pounds per square inch. The 10 seats are, or may be, hardened to reduce wear, are ground true and are carefully finished on their peripheries, so that when located in their proper positions the seats will be parallel to each other and their axes will 15 coincide. Each seat has a screw threaded opening 55 to receive a means for removing it. The seats are inserted in place from opposite ends of the casing, and each is held in position by the valve receiving member 20 or stop 56 at the side thereof remote from the other, Figs. 13 and 14. The valve stop has a small circular projection 57 formed on the same side as the valve seat and has a flat surface that engages the central portion 25 of said seat to hold it in place. The projection extends through the hole 58 in the disk valve and acts as a guide to direct its axial movements and also to prevent it from moving sidewise. The stop is also provided 30 with means, such as the holes 59, to prevent air from being trapped in back of the valve and acting to unduly cushion its opening movements. These holes also permit air to have access to the valve on its discharge side 35 to close it, thereby doing away with all springs. The holes also serve to break any oil film which might otherwise tend to hold the valve open. The stop is also provided with a screw threaded opening 60 to receive 40 a removing tool. As before stated the valve receiving member or seat 49 is seated on the ring member 48 and the stop 56 engages the valve seat. The stop is held in place by a screw 61 that is threaded into 45 the head 62 of the valve casing. The end of the screw is rounded and the tip end thereof slightly enters the screw hole 60 which forms a seat to hold the stop against sidewise movement. It will thus be seen 50 that one device, *i. e.*, the bolt, has the function of holding the seat, the stop and the valve. The screw is provided with a lock nut 63 and between its end and the head is a soft copper washer 64 to make an air-tight joint 55 at this point. The head 62 may also be provided with a similar washer between it and the casing. In any event this joint must be airtight. Air enters the casing by the port 54 which communicates with the chamber 53 between the seats and passes therefrom through the holes or passages 51 past the disk valves 39 and thence to the discharge pipe 64^a leading directly or indirectly to the high pressure suction valve. On the 60 discharge stroke the valves are raised from

their seats by the air delivered by the low pressure piston of the compressor and on the suction stroke of the piston the air on the discharge side causes them to close. It will thus be seen that all springs are done away with, which makes for simplicity and reliability in operation and reduces the cost of manufacture and operation. The same advantages as to silence and absence of pounding apply to these valves as to those 70 shown in Fig. 3.

Referring now to Fig. 2, 24 indicates the casing of the high pressure valves. It is provided with a cooling chamber 65 that receives water from any suitable source. It is also provided with two openings, in the present instance, to receive valve casings. Where the volume of air to be handled is greater, a greater number of valves and casings may be employed. 66 indicates the high pressure delivery valve receiving member which forms the valve seat. It is slightly cored at its lower side or end to make a good fit with a similarly shaped opening or shoulder in the valve casing. The 80 details of this seat are best shown in Figs. 7 and 8. The seat is provided with a flat ground surface 67 to receive the valve, and also with axial passages, openings or ports 68 through which the air flows directly from the high pressure cylinder of the compressor. The upper side or surface is provided with an annular groove 69 and a small V-shaped groove 70. The seat is also provided with a screw threaded opening to receive a tool for removing it. 71 indicates the high pressure valve receiving member which forms the stop or cover; it is tubular in form and is provided with an annular projection 72 that fits into the groove 69, 100 Fig. 7. Between the bottom of the groove and the end of the projection is a soft copper washer that is pressed into the V-shaped groove 70 to make an air-tight joint. The valve 72 is of the disk type heretofore described and is illustrated in section and plan in Figs. 5 and 6. The outer end of the valve cover is somewhat enlarged and provided with a groove containing a copper washer. Mounted on the end of the cover is a head 73 having a projection that fits into the groove. The head is secured in place by stud bolts 74. The head is also screw threaded to receive a nut 75 which holds the air conveying pipe in place. 110

In operation, the compression stroke of the piston raises the valve from its seat and exposes the ports 68. Air rushes through these openings and is discharged through the central opening in the valve 72, the port 125 85 in the cover registering with said opening. In the cover are ports 86 that assist in closing the valve on the suction stroke in the manner referred to in connection with ports 59 of Figs. 4, 13 and 14. The suction 130

valve is of the same construction as the delivery valve and is interchangeable therewith. In this case, however, the valve receiving member 76 which serves as the valve seat is formed on the tubular member 77, the latter being provided with ports or passages 78. The valve receiving member which serves as the stop is formed by the plug 79 which makes a taper fit with a shoulder of the casing. It is provided with ports or passages 80 that communicate with the high pressure cylinder. To avoid any mistake in assembling the parts, the delivery valve seat 66 and the suction plug or stop 79 are made of dissimilar lengths. The parts are held in position by the same means used for holding the delivery valve. This arrangement has the advantage that the openings in the casing 24 can be of the same 20 diameter and hence the same tools can be used for forming them. Also that the heads 73, securing studs, etc., can be made in quantities and kept in stock. In so far as it is possible the parts are made interchangeable to save expense. All parts are made to exact size so that new parts can be supplied to take the place of old with the certainty that they will fit. The air delivered by the valve 72 is under high pressure, say 1000 pounds per square inch as an example. This means that all of the joints must be very carefully made and that the parts should be cooled as fully as possible to prevent overheating and hence destruction.

As before stated the valves and their seats and stops must be made with the greatest care, all of the coöperating surfaces being ground or otherwise finished true and maintained in fixed parallel relation to each other if the best results are to be obtained. Owing to the very small mass of the valves and to the very small movement thereof their life will be long, and the noise made by them in opening and closing will be so small as to be negligible.

In accordance with the provisions of the patent statutes we have set forth what we believe to represent the best embodiment of our invention; but it is to be understood that the drawing is only illustrative and that our invention can be carried out by other means.

What we claim as new, and desire to secure by Letters Patent of the United States

is:—

1. The combination of a casing having a generally cylindrical bore with annular shoulders near its middle and an opening between said shoulders, valve receiving members on said shoulders with the space between them in communication with said opening, each of said members having annularly arranged openings extending in opposite directions from said space, an additional valve receiving member at the side of

each of those aforesaid remote from the other, means acting through each of the latter valve receiving members to keep the first-mentioned members in place, there being means of communication between the side of each of the first-mentioned valve receiving members remote from the other and the exterior of the casing, and valve disks between the valve receiving members secured against each shoulder as aforesaid.

2. The combination of a casing having a generally cylindrical bore with an annular shoulder and an opening at one side of said shoulder; a valve receiving member mounted in said bore on said shoulder; another valve receiving member mounted in said casing against the end of the first; and a cover at the end of said casing bearing upon said latter member and serving to secure the members in place, each of said members having annularly arranged openings therethrough and the member adjacent the cover having at its side remote from the cover a portion extending into a bore in the other, said portion having a finished surface to serve as a valve seat, and said member mounted on the shoulder of the casing having a central space within it for containing a compression spring; a disk valve arranged between said members; and a compression spring in said central space which acts to urge said valve against the seat.

3. The combination of a casing having a generally cylindrical bore with an annular shoulder and an opening at one side of said shoulder; a valve receiving member mounted in said bore at the other side of said shoulder; another valve receiving member mounted in said bore against the other end of said first-mentioned member; a cover for the corresponding end of said bore which bears upon said last-mentioned member and so holds both members in place, said last-mentioned member having at its side remote from the cover a portion extending into a depression in the adjacent side of said first-mentioned member with its surface finished to form a valve seat, there being a space between said seat and the adjacent surface of said first-mentioned member and annularly arranged ports in both said members opening in opposite directions from the said space, the ports in the first of said members communicating with the opening in the casing aforesaid, and said second member having a central opening or space and a peripheral groove and ports through its wall from said groove into said central space, and a passage in said casing leading from said peripheral groove to the exterior thereof.

4. In a fluid controlling valve, the combination of a casing having a generally cylindrical bore with an annular shoulder; a valve receiving member on said shoulder; an additional valve receiving member in said

bore at the side of said first member remote from said shoulder; a part secured to said casing and bearing upon the second member aforesaid whereby both members are held in 5 place, said second member having a central space in it which is in communication with passage means for the fluid controlled by the valve, one of said members having a central depression and the other of said members 10 having a portion extending thereinto with its surface finished to form a valve seat, and there being a space between said seat and the adjacent surface of the other member and annularly arranged ports extending through the members to said space; and a 15 valve disk in the space aforesaid between said members.

In witness whereof we have hereunto set our hands and seals this 23rd day of May, 1912.

Correction in Letters Patent No. 1,088,264.

It is hereby certified that in Letters Patent No. 1,088,264, granted February 24, 1914, upon the application of Charles Day and George E. Windeler, of Stockport, England, for an improvement in "Valve Mechanism for Air-Compressors," an error appears in the printed specification requiring correction as follows: Page 2, line 123, for the word "securing" read *receiving*; and that the said Letters Patent should be read with this correction therein that the same may conform to the record of the case in the Patent Office.

Signed and sealed this 24th day of March, A. D., 1914.

J. T. NEWTON,
